DISPLAY CARTON

Paul L. Anthony, Pelham Manor, N. Y., and Leo E. Croy, Neenah, Wis., assignors to Marathon Paper Mills Company, Rothschild, Wis., a corporation of Wisconsin

Application January 20, 1938, Serial No. 185,992

6 Claims. (Cl. 206—44)

This invention relates to a carton for packaging articles so as to be visible while in the package.

An important object of this invention is the provision, in a manner as hereinafter set forth, 5 of a carton designed to be quickly and easily assembled, and so formed that upon being filled with the commodities to be sold, the articles will be held in a compact manner and at the same time will be on view for display.

10 The invention contemplates the provision of a carton made from a single blank having a transparent sheet glued to its margins so as to provide a window, a carton having an elongated bottom terminating in end flaps, and further having side 15 walls terminating at each end in flap members designed to interlock with the adjacent end flap member to hold the side walls and the first mentioned flaps of the carton in upright position. When the carton is thus assembled articles for 20 sale may be arranged therein so that they are visible.

A further object of this invention is the provision of a carton made from a single blank having a transparent window for displaying the goods 25 within the carton, the said carton being shipped in flat knocked-down condition to the user.

The invention will be best understood from a consideration of the following detailed description taken in connection with the accompanying drawings 30 forming a part of this specification, with the understanding that the invention is not confined to any strict conformity with the showing of the drawings but may be changed and modified so long as such changes and modifications mark no 35 material departure from the salient features of the invention as expressed in the appended claims.

In the drawings:

Figure 1 is a perspective view of the display carton.

40 Figure 2 is a plan view of the blank for forming the carton.

Figure 3 is a plan view of the completed carton in flat condition.

45 Figure 4 is a fragmental perspective view of the carton showing the inner closure flap in folded position.

Figure 5 is a view similar to Figure 4 showing the marginal flaps folded over the inner closure flap, and

50 Figure 6 is a fragmental perspective view of one end of the carton showing the outer closure flaps in interlocked relation.

Referring to the drawings, wherein like numerals refer to corresponding parts, the carton is 55 made from a single blank of foldable material

such as cardboard which is provided with longitudinal score lines 1, 2, 3, and 4 forming a bottom panel 12, side walls 11 and 13 and top marginal panels 10 and 14. The bottom panel 12 is scored adjacent both ends along lines 7 to provide end 5 flaps 18 which are free from the next adjacent flaps along slits 31, 32 and 35 and 36, respectively, at each end of the bottom panel, and constituting inner closure flaps for the ends of the carton. Side walls 11 and 13 are scored adjacent their 10 ends along lines 6 and 8, respectively, to provide outer closure flaps 16, 16', 20 and 20' which are free from the next adjacent flaps along slits 30, 15 33, 34 and 37. Flaps 16' and 20 are provided with tongue portions 25. Flaps 16 and 20' are provided with slits 26 and 27 for receiving the tongue portions 25 when the carton is set up. Marginal panels 10 and 14 are provided with score lines 5 and 9, respectively, adjacent their ends for forming free end flaps 15 and 22 at their respective 20 ends.

A transparent sheet material 40 of sufficient width to overlap the marginal portions 41 and 42 of panels 10 and 14 is affixed to the panels 10 and 14 as shown in Figures 1 and 3. The transparent 25 sheet material 40 is preferably of sufficient length to extend the combined length of the marginal panels and end flaps 15 and 22 as shown in Figure 3.

In manufacturing the carton, the cardboard 30 blank as illustrated in Figure 2, is folded on score line 3 so that panels 13 and 14 are in face contact with bottom panel 12 as shown in Figure 3. Panel 10 is then folded over on panel 11 along score line 1 and a transparent sheet 40 is then glued to 35 the marginal portions 40 and 41 as shown in Figure 3. The carton so formed is shipped to the user in flat knocked-down condition.

In using the carton for packaging goods therein, side walls 11 and 13 are folded up at right 40 angles to the bottom panel as shown in Figure 4. The goods to be packaged are then inserted through the open ends of the carton and placed on the bottom panel 12 and beneath the transparent window 40. End flaps 18 are then folded 45 up at right angles to the bottom panel as shown in Figure 4. Flaps 15 and 22, together with the ends of the window 40 glued thereto, are then folded over flaps 18 as shown in Figure 5. Flaps 16 and 20, and 16' and 20' are then folded over the ends 50 of the carton and interlocked by inserting tongue 25 through slit 26 as shown in Figure 6. The final package will then appear as shown in Figure 1.

The carton construction may be modified in many ways. For example, the marginal top panels 55

- 10 and 14 together with flaps 15 and 22 may be omitted and the transparent sheet may be used of such width that the longitudinal margins of same may be glued to the side walls 11 and 13.
- 5 Free end portions may be provided on the transparent sheet which are adapted to be folded over the ends of the carton and retained in position by the end closures. These free end portions may be omitted if desired.
- 10 The carton construction may be modified in any suitable manner. For example, the inner closure flaps 18 may be omitted if desired. The construction of the outer closure flaps may also be modified if desired in any suitable manner
- 15 other than that herein disclosed. If desired the end flaps 15 and 22 may be omitted and the free end portions of the transparent sheet are merely folded over the ends of the carton and retained in position by the outer closure flaps.
- 20 It is therefore to be understood that the invention is not restricted to the particular construction of the blank herein disclosed and that the principle of the window construction may be utilized on any suitably shaped blank.
- 25 The carton construction herein described provides a simple and economical construction requiring a minimum amount of carton material as practically no stock is wasted in forming the carton. According to the construction of the
- 30 present invention no windows are cut out of the body of the stock as is necessary in previous display carton constructions so that there is a great saving produced in the manufacture of the cartons. Furthermore the present construction
- 35 provides a very striking and effective display for the contents within the carton as a maximum visibility is provided since the window extends the full length of the carton and there is no obstruction at the ends of the window. The carton can also be readily packed with the goods
- 40 to be packaged and it can be set up with speed without requiring any expensive equipment.
- From the foregoing description it will be readily seen that there has been provided a display carton for the purpose set forth which is of
- 45 unique and novel design, and in which the articles for sale may be kept on view and at the same time to be kept wrapped and clean.
- We claim:
- 50 1. A display carton formed from a blank of foldable material comprising a bottom wall, side walls, and marginal top panels coextensive with the side walls and integral therewith, inner closure flaps extending from each end of the said
- 55 bottom wall, said inner closure flaps being substantially of the same width as the said side walls, marginal end flaps extending from each end of the said marginal top panels, outer closure flaps extending from each end of the side walls, said outer closure flaps being provided with complementary tongue portions and slits for interlocking same, and a transparent sheet material glued to the outer portions of the said marginal panels and the marginal end flaps to
- 60 provide a window for displaying the goods placed within the carton.
- 65 2. A display carton formed from a blank of foldable material comprising a bottom wall, side walls, and marginal top panels coextensive with the side walls and integral therewith, inner closure flaps extending from each end of the said
- 70 bottom wall, said inner closure flaps being substantially of the same width as the side walls, marginal end flaps extending from each end of the said marginal top panels, the length of said

marginal end flaps being substantially equal to the width of said side walls, outer closure flaps extending from each end of the side walls, said outer closure flaps being provided with complementary tongue portions and slits for interlocking same, and a transparent sheet material glued to the outer portions of the said marginal panels and marginal end flaps to provide a window for displaying the contents within the carton.

3. A display carton formed from a blank of foldable material comprising a bottom wall, side walls, and relatively narrow marginal top panels coextensive with the side walls and integral therewith, inner closure flaps extending from each end of the said bottom wall, marginal end flaps extending from each end of the said marginal top panels, the length of said marginal end flaps being substantially equal to the width of said side walls, outer closure flaps extending from each end of the side walls, said outer closure flaps being provided with complementary tongue portions and slits for interlocking same, and a transparent sheet material glued to the marginal panels and the marginal end flaps to provide a display window for said carton, said transparent sheet being of a sufficient width to overlap the marginal top panels and of a length substantially equal to the combined length of a side wall and the marginal end flaps at each end thereof.

4. An integral blank for forming a display carton formed from a foldable material comprising a bottom wall, side walls, and relatively narrow marginal top panels coextensive with the side walls and integral therewith, inner closure flaps extending from each end of the said bottom wall, outer closure flaps extending from each end of said side walls, said outer closure flaps being provided with complementary tongue portions and slits for interlocking same, marginal end flaps extending from each end of the said marginal top panels, the length of said flaps being substantially equal to the width of said side walls, outer closure flaps extending from each end of the side walls, and a transparent sheet material glued to the marginal top panels and marginal end flaps to provide a display window for the carton.

5. An integral blank for forming a display carton formed from a foldable material comprising a bottom wall, side walls, and marginal top panels, inner closure flaps extending from each end of the said bottom wall, said inner closure flaps being substantially of the same width as the side walls, end flaps extending from each end of the said marginal top panels, the length of said flaps being substantially equal to the width of said side walls, outer closure flaps extending from each end of the side walls, said outer closure flaps being provided with complementary tongue portions and slits for interlocking same, and a transparent sheet material glued to the outer portions of the said marginal panels to provide a window for displaying the contents within the carton and having free end portions glued to the said end flaps extending from the marginal top panels, said free end portions being adapted to be folded over the ends of the carton and retained in position by said outer closure flaps.

6. A display carton formed from a blank of foldable material comprising a bottom wall, side walls, and marginal top panels coextensive with the side walls and integral therewith, inner closure flaps extending from each end of the said

- bottom wall, said inner closure flaps being substantially the same width as the side walls, marginal end flaps extending from each end of the said marginal top panels, outer closure flaps extending from each end of the said side walls, said outer closure flaps being secured to each other and a transparent sheet material glued to the marginal panels and marginal end flaps to provide a win-

dow for displaying the contents within the carton, said transparent sheet having free end portions adapted to be folded over the end of the carton and retained in position by said outer closure flaps.
